UNITED STATES PATENT OFFICE

2,601,316

DRAIN FOR FLOATING ROOF TANKS

Frederick D. Moyer, Chicago, Ill., assignor to Chicago Bridge & Iron Company, a corporation of Illinois

Application October 16, 1948, Serial No. 54,922

4 Claims. (Cl. 220—26)

1

This invention relates to a drain and more particularly to a drain for a floating roof tank.

Drainage means must be provided for a floating roof tank designed for use in an area where precipitation is to be expected. Generally such drains comprise a sump in the floating roof toward which the deck of the roof is inclined. In some installations the sump opens directly under the roof to the stored product and rain water, being heavier than products commonly stored in such tanks, will eventually find its way to the bottom. This particular form of drain is undesirable as it takes some time for all the water to reach the bottom of the tank with the result that the stored product is water-contaminated for a good part of the time.

It has been proposed to alter this type of drain by the use of a flexible or bendable drain hose connected to the sump and opening to the bottom of the tank. In such installations a 4" to 6" layer of water is maintained on the bottom of the tank and means may be provided at the side of the tank for draining off the water as it accumulates on the bottom.

It has also been suggested to connect a flexible or bendable pipe directly from the sump to the exterior of the tank in order that the tank contain no free water at any time.

In any of the above installations the drain may comprise a flexible hose or a jointed pipe, either of which drains are referred to herein as bendable drains.

Experience has shown that one of the first elements to wear out on a floating roof tank is the drain and it has heretofore been necessary to empty the entire tank in order that a worn out drain may be replaced. Bendable drains also cause difficulty when they are used in floating roof tanks in areas where freezing weather occurs. In such areas the water overlying the bottom of the tank often freezes and if during such freezing the drain is at least partially resting upon the bottom, as it does when the roof is at some position other than its highest position, the drain itself will become imbedded in the ice and will rupture if further liquid is introduced into the tank causing the roof to rise.

I have invented and am herein disclosing and claiming a drain for a floating roof tank which eliminates the difficulties above referred to. By this invention I provide a drain which may be repaired or replaced without taking the tank out of operation and I further provide means for maintaining the drain above the bottom of the tank at all times during operation of the tank so as to prevent freezing of the drain to the bottom.

The invention will be described in conjunction with the specific embodiment shown in the accompanying drawings in which:

2

Fig. 1 is a vertical section through a portion of a floating roof tank showing a part of the floating roof and showing a platform which is part of my drainage means resting upon the bottom of the tank; and

Fig. 2 is a top plan view of the platform shown in Fig. 1.

Referring now to the drawings I show a floating roof 10 being in the form of a double deck roof having an upper deck 11 and a lower deck 12. The upper deck slants downwardly toward a sump 13 and is provided with a manhole 14 opening through the roof. A circular plate 15 is connected to the sides of the sump 13 and provided with a central circular opening 16. A drain connection 17 is firmly attached to a second circular plate 18 positioned over and secured to the plate 15 and provided with an opening 19 through which rain water may drain. Connected to the member 17 is a flexible drain hose 20.

Resting upon the bottom 21 of the tank directly beneath the sump 13 is a platform 22. In the specific embodiment shown, the platform comprises a plurality of rods 23 radiating outwardly from a central metallic disk 24, attached to a pipe section 34, to form a foraminous bottom for the platform. The pipe 34 is centered over a pipe section 35 upstanding from the bottom of the tank to maintain the platform 22 centered beneath the sump. Adjacent the outer edge of the platform the rods are bent 90 degrees upwardly to form an upstanding edge 25 and are then bent 180 degrees so that they extend downwardly to the bottom of the tank to support the bottom of the platform above the tank bottom. A circular rod 26 encircles the platform and is connected to the rods 23 at the point where they are curved 180 degrees. The distance from the platform to the tank bottom normally is from 6" to 8" and in any event is sufficient to maintain the bottom of the platform above the level of any water overlying the bottom of the tank.

A pipe 27 is fixed to the bottom of the tank and provided with a drain opening 28. Upstanding from the pipe 27 is a member 29 adapted to be connected to the pipe by means of a bayonet clamp 30. The member 29 is positioned directly beneath the manhole 14 and is provided with a handle 31 by which it may be grasped by a workman standing on top of the deck when the roof is in the position shown in Fig. 1. At this point the roof normally will be resting upon its support rather than being supported directly by the liquid within the tank although it is clear that by adjusting the length of the member 29 that member can be made accessible from the manhole when the roof is in a slightly higher position and floating on the liquid. A workman on the roof may then reach down through the manhole

and grasp the handle 31 to rotate the member 29 approximately one-quarter turn whereupon the member may be withdrawn from the pipe 27 and out through the manhole.

The member 29 is also provided with a fitting 32 adapted to be secured to a corresponding fitting 33 secured to the lower end of the hose 20 and drain water coming down the hose is lead out to the bottom of the tank through the opening 28. The fittings 32 and 33 are secured together so as to impart no twist to the hose when the roof is in its lowest position in the tank. When the roof rises the hose will twist through a number of degrees determined by the amount of loops in the hose when it is entirely supported by the platform. I prefer to arrange the platform and the hose so that when the roof is in its lowest position the hose is in a single complete loop and therefore movement of the roof from its lowest to its highest position will twist the hose through 360 degrees. The torsional effect so exerted on the hose insures that it will form a single loop upon the downward movement of the roof within the tank. The diameter of the platform then is approximately equal to the diameter of the loop formed by the hose. This will be approximately the total distance of vertical movement of the roof divided by pi.

The customary drain outlet may be used to drain out water which accumulates on the tank bottom. The outlet may be automatically or manually operated so as to prevent water from rising to a point high enough to come into contact with the hose.

When it becomes desirable to replace the hose 20, the cover (not shown) of the manhole 14 may be removed and the member 29 withdrawn through the manhole as just described. This, of course, will bring the lower end of the hose 20 out upon the deck. The upper end of the new hose may then be secured to the fitting 33 on the end of the old hose and dropped down into the tank. Removal of the plate 18 and withdrawal of the connection 17 and the upper end of the hose through the sump 13 may then be accomplished and the old hose may be entirely withdrawn through the sump; such action, of course, will draw the new hose thereafter. The upper end of the new hose may then be connected to the member 17 and the lower end connected to the member 29 and both of said members may be replaced in the tank. In such manner a defective or damaged hose may be replaced without the necessity of completely draining the tank without the necessity of sending a man under the roof.

The purpose of the platform 22 is to maintain the drain above the bottom of the tank in all positions of the roof. To that end I so proportion and locate the platform that the drain is held within the confines thereof with downward movement of the roof. Thus, for a central drain the platform is located in the center of the bottom and is generally located directly beneath the sump to which the drain is attached.

While I have shown and described my invention in its preferred embodiment it should be understood that it is capable of many modifications. I therefore do not intend to be limited to the exact embodiment shown but rather intend that my invention be construed broadly

in accordance with the spirit and scope of the appended claims.

I claim:

- 5 1. In a floating roof tank having a floating roof, and a sump and manhole in the roof, drainage means for the roof comprising a bendable drain having one end connected to the sump, an upstanding member fixed to the bottom of the tank a removable member extending upwardly above the bottom of the tank beneath the manhole and having clamping means for removably securing said members together, and means for attaching the other end of the drain to the removable member, said drain being in an untwisted condition when the roof is in its lowest position within the tank.
- 10 2. In a floating roof tank having a floating roof, and a sump and a manhole in the roof, drainage means comprising a bendable drain having one end fixedly connected to the sump, a platform spaced above the bottom of the tank beneath the drain and a removable member upstanding above the platform at all positions of the roof within the tank and said member having the other end of the drain fixedly attached thereto, said member being accessible from and removable through said manhole when the roof is floating near the bottom of the tank and means for supporting said platform above the bottom to support the drain above water in the bottom of the tank at all times during normal operation of the tank, said platform supporting the drain in an untwisted coil when the roof is in its lowest position in the tank.
- 15 3. In a floating roof tank having a floating roof, and a sump and a manhole in the roof, drainage means for the roof comprising a bendable drain having one end connected to the sump, an upstanding pipe fixed to the bottom of the tank and having openings therein adjacent said bottom, a member extending upwardly from said pipe and having clamping means for removably attaching said member to said pipe, said member and pipe being located beneath the manhole, and means for attaching the other end of the drain to said member, said attaching means being spaced from the bottom of the tank when said member is attached to said upstanding pipe.
- 20 4. Apparatus of the character described in claim 3 in which support means are provided for the drain comprising a platform spaced above the bottom of the tank and positioned beneath said drain and means for supporting said platform above the bottom of the tank, said platform having a foraminous bottom with an upstanding peripheral edge to receive and maintain substantially the entire drain out of contact with the bottom of the tank.
- 25 50 60 65 70 75 80 85 90 95
